CLAIM

The ornamental design for a water bladder securing strap system, as shown and described.

DESCRIPTION

FIG. 1 is a front elevation view of a water bladder securing strap system showing the new design;
FIG. 2 is a back elevation view thereof;
FIG. 3 is a left-side view thereof;
FIG. 4 is a right-side view thereof;
FIG. 5 is a top plan view thereof;
FIG. 6 is a bottom plan view thereof;
FIG. 7 is a perspective view thereof;
FIG. 8 is another perspective view thereof;
FIG. 9 is an enlarged view of the encircled portion in FIG. 7;

FIG. 10 is an enlarged view of the encircled portion in FIG. 7;
FIG. 11 is an enlarged view of the encircled portion in FIG. 1; and,
FIG. 12 is an enlarged view of the encircled portion in FIG. 7.

The equal length broken lines depicting a water bladder represent environmental structure that forms no part of the claimed design. The remainder of the equal length broken lines depict portions of the Water Bladder Securing Strap that form no part of the claimed design.

The dash-dot lines in FIGS. 1, 7, 9, 10, 11, and 12 illustrate the cut lines of the enlarged view indicators and form no part of the claimed design.
